ATTORNEY

UNITED STATES PATENT OFFICE.

FREDERICK L. BRAENDER, OF MONTCLAIR, NEW JERSEY.

DESIGN FOR AN AUTOMOBILE TIRE.

Application filed August 4, 1924. Serial No. 10,365. Term of patent 14 years.

To all whom it may concern:

Be it known that I, FREDERICK L. BRAENDER, a citizen of the United States, residing at Montclair, in the county of Essex and State of New Jersey, have invented a new, original, and ornamental Design for Automobile Tires, of which the following is a specification, reference being had to the accompanying drawings, forming a part thereof, wherein—

Fig. 1 is a plan view of the new design, and

Fig. 2 is a section on the line 2—2, Fig. 1.

I claim:—

The ornamental design for an automobile tire, as shown.

FREDERICK L. BRAENDER.
